UNITED STATES PATENT OFFICE.

ALLEN E. WHETSTONE, OF WOOD LAKE, NEBRASKA.

GATE.

1,046,920.

Specification of Letters Patent. Patented Dec. 10, 1912.

Application filed May 18, 1912. Serial No. 698,271.

To all whom it may concern:

Be it known that I, ALLEN E. WHETSTONE, a citizen of the United States, residing at Wood Lake, in the county of 5 Cherry and State of Nebraska, have invented certain new and useful Improvements in Gates, of which the following is a specification.

The invention relates to that type of gates 10 wherein the counterbalanced lever is connected by a link to effect manipulation of the gate, and the object in view is the impartation of a thrust to the gate at such point as to enable the lever mechanism to 15 attain the maximum leverage effects and to thereby swing the gate from closed position with a minimum expenditure of stress.

For a full understanding of the present 20 invention, reference is to be had to the following description and to the accompanying drawings, in which—

Figure 1 is a view in elevation of a gate 25 constructed in accordance with my invention, showing in dotted lines the movement of the gate from its closed to open positions, a portion of the supporting standard being broken away; and Fig. 2 is an end elevation of the same.

Throughout the following detail description 30 and on the several figures of the drawings, similar parts are referred to by like reference characters.

In carrying out the invention I employ a gate 1 which may be of any ordinary construction and shape best suited for the purposes for which it is desired. In the drawings, however, the gate comprises the usual horizontal frame members 2 and a diagonal brace member 3 suitably secured in the frame 40 of the gate itself. The gate 1 is pivotally mounted at its lower inner corner on the cross-rod 4 mounted in the lower portion of the vertical spaced standards 5 between which the gate is adapted to be operated. 45 The opposite end portion of the gate preferably rests upon a suitable supporting block 6 adjacent the jamb posts which are not shown in the drawing.

At a suitable point in one of the vertical 50 standards 5 is located a pintle 7 upon which is fulcrumed intermediate its ends, a balancing lever 8 which extends downwardly at an incline and has provided on its free end a counterweight 9, the latter being preferably slidably mounted on said lever for adjusting purposes. The opposite extremity

of the inclined balancing lever 8 is pivotally connected with one end of the link-bar 10, the latter being likewise mounted at the upper free end of the gate 1, as indicated 60 at 11.

It is to be noted that as above described, the gate proper may be of extremely light material and it is contemplated that the balancing lever be so proportioned in length 65 that the weight 9 will relieve any unusual strain on the gate due to its mounting, throughout the entire operation of opening and closing said gate. The particular point of pivot of the gate opposed to the point 70 upon which the balancing lever exerts its force is important, as will be obvious to anyone skilled in the art to which this device refers.

In the actual use of my invention, the gate 75 extends in the usual manner across the roadway, beside which may be provided the usual approach posts at both sides of the gate but since these are of the ordinary conventional usage they have not been shown in the drawing. An operating rope 12 extends from the approach posts aforesaid to the upper frame member of the gate 1 where it is secured, as indicated at 13, passing over a pulley 14 swiveled on the upper cross-bar 80 15 connecting the spaced standards 5. From the foregoing it will be obvious that to operate the gate to open or close the same, a very slight pull is exerted upon the rope 12, imparting a slight momentum to the 90 gate, which, by action of the weighted balancing lever, moves on its pivot in a vertical plane until it assumes its ended position, shown in dotted lines in Fig. 1. Having in view the inclined position of the balancing lever and its link connection, the gate is shoved by the former throughout its movement and the slight momentum which is given thereto when the rope 12 is actuated, naturally tends to prevent any likelihood of 95 100 the gate from stopping at its center of movement.

There are numerous advantages of my particular construction, some of which have hereinbefore been mentioned, and it is to be 105 noted that by reason of the incline of the balancing lever 8, it is in an operative position both when the gate is closed and when opened, and when in the latter position only a minimum amount of space is required to 110 accommodate the same. The spaced standards 5, between which the gate operates, act

as a guide therefor throughout its movement, in an obvious manner, and prevent any side swaying when operated while the wind is blowing.

5 Slight modifications may readily be made in the structure without departing in any way from the spirit of the invention and within the scope of the claims hereto appended.

10 Having thus described the invention, what is claimed as new is:

1. The combination, with a standard, of a gate pivotally mounted to swing vertically, a lever pivoted to the standard in the vertical line of the pivot of the gate and spaced therefrom and extending outwardly from the pivot across a portion of the gate, and a link pivoted at its lower end to the lower end of the lever, said link extending upwardly

and being pivoted to the gate at a point 20 above the horizontal line of the pivotal connection of the lever to the standard.

2. The combination, with a standard, of a gate pivoted adjacent the standard, a lever pivoted to the standard and extending 25 downwardly on an incline past a portion of the gate, and a link pivotally connected to the lower end portion of the lever and extending upwardly to and pivotally connected with the upper portion of the gate 30 adjacent the free end thereof.

In testimony whereof I affix my signature in presence of two witnesses.

ALLEN E. WHETSTONE.
